tion of Ohio

Application May 22, 1956, Serial No. 41,596

Term of patent 14 years

(Cl. D13—1)

Fig. 1

Fig. 2

In the drawings,

Fig. 1 is a front perspective view of a metal door embodying my new design; and

Fig. 2 is an enlarged, partially broken away vertical section taken on line 2—2 of Fig. 1.

Shading on the drawing represents contrastingly colored areas.

I claim:

The ornamental design for a metal door, as shown and described.
